(57) **CLAIM**

The ornamental design for an extracorporeal charger unit for medical implant, as shown and described.

DESCRIPTION

The patent or application file contains at least one drawing executed in color. Copies of this patent or patent application publication with color drawing(s) will be provided by the Office upon request and payment of the necessary fee.

1. Extracorporeal charger unit for medical implant
2. Extracorporeal charger unit for medical implant
3. Extracorporeal charger unit for medical implant
4. Extracorporeal charger unit for medical implant
  - 1.1 : Top
  - 1.2 : Right
  - 1.3: Bottom
  - 2.1 : Top
  - 2.2 : Right
  - 2.3 : Bottom
  - 3.1 : Top
  - 3.2 : Right
  - 3.3 : Bottom
  - 4.1 : Top
  - 4.2 : Right
  - 4.3 : Bottom

In reproductions 2.1, 2.2 and 2.3, the top and bottom part of the charger are of different colors; that is, the solid gray shading (bottom part) is signifies a different color than the unshaded part (top part).

(Continued)

In reproductions 2.1, 2.2 and 2.3, the top and bottom part of the charger are of different colors; that is, the bottom part is a light blue color, and the unshaded top part may be any color.

In reproductions 4.1, 4.2 and 4.3, the top and bottom parts of the charger are shown with colors of one possible embodiment.
